ENGINE FOR TRANSMITTING FORCES
DEVELOPED THEREIN

Hal De Waide, Seattle, Wash.

Application April 23, 1947, Serial No. 743,238

10 Claims. (Cl. 123—19)

1

My invention relates to the art of engines for transmitting forces developed therein. More particularly my invention relates to an engine characterized by the use of liquid as a power transmitting means between a fluid pressure chamber or working chamber and a mechanical torque delivery or converting means.

My invention will be set forth primarily herein as applied to internal combustion engines, but it is to be understood that it is not to be restricted to any such specific application but extends to all uses where like conditions exist in whole or in part, such as in any engine receiving its fuel or energy through externally developed pressure and running as a motor. Be it particularly noted that where examples are cited and modifications are set forth that the same are given as illustrations and not as limitations unless the context otherwise indicates.

Definite mechanical limitations are present in the conventional reciprocating engine where the power is transmitted between the piston member and the drive or crankshaft member through the mechanical linkage of a rigid connecting rod, commonly known as the "crank chain" linkage, which linkage provides a fixed geometrical relationship.

My invention relates to a device which uses a liquid in lieu of the conventional rigid connecting rod for the transmission of energy between a reciprocating piston member and a rotating shaft. In my invention there is suitably connected to the rotating shaft an eccentrically mounted rotating liquid displacement member and mounted in a housing having a plurality of compartments. The operation of said displacement member alternately impells and retracts the liquid in each partitioned part of the housing. This alternate flow within the compartments produces a reciprocating liquid body, similar to the piston action of a conventional engine.

A primary object of the invention herein set forth is the providing of instrumentalities herein called abutment members to hold off the expansion pressure of the power transmitting liquid as respects a certain circumferential portion of the displacement member and thereby allow and direct the expansion pressure of the power transmitting liquid to selectively act directly only upon a certain other portion of the displacement member; that is, that portion where the greatest leverage may be obtained.

In connection with thus providing for greatly increased efficiency of this type of an engine, there is involved the relieving of pressure on cer-

2

tain portions of the circumference of the displacement member. Furthermore, the power transmitting liquid, being subject to the heating of the explosive or force producing fluids in the working chamber, become heated and it is a primary purpose of my invention to provide for the continued cooling of the power transmitting liquid.

The providing of an engine employing liquid as the power transmitting means presents at the outset fundamental difficulties, for example, it may be questioned how is a liquid means having no tensile strength (only compression strength) to be used in a high speed reciprocating engine as the power transmitting means? How, with such a medium, is a predetermined spaced relationship between the power producing fluid operating in an expansible chamber type of engine to be maintained with respect to its power shaft? How is such a power transmitting liquid to be sealed between its moving members where high velocity wear may be expected? How is balanced volumetric relationship of the power transmitting liquid to be established and maintained in relation to a uniform volume of working fluid? How is the jetting action of liquids in motion to be controlled? How may an engine be provided which may develop greatly increased torque without conventional torque increasing means, such as conventional transmission means, and this without loss of maximum operating efficiency? These are only a few of the problems which my invention and discovery has solved.

Furthermore, besides crank-chain linkage limitation, another fundamental difficulty inherent in internal combustion engines relates to its ability to breathe, that is, getting a sufficient quantity of air into a given space for combustion and the elimination therefrom of the exhaust gases. Increasing the valve area when exposed to the high temperature gases of combustion in the conventional type of engine does not solve such air problem because the increased area accelerates or builds up a contra-acting sealing problem, due for one reason to increased warping problems and increased wear due to lubricating difficulties, to say nothing of involved increased inertia and functional mechanical problems. A fundamental purpose of my discovery or invention is to overcome the difficulties and limiting restrictions to air flow and velocity of conventional internal combustion engines by providing a type of engine of my invention employing liquid as the power transmitting means. Accordingly my discovery

and invention involves providing for proper lubrication and cooling of valve mechanism.

Still furthermore, the engine in common use and of conventional design with its rigid crank chain linkage has certain inherent positive restrictions, such as its space volume requirement for given power production and weight. A fundamental purpose of my discovery and invention is to provide an engine of a design of far greater flexibility as respects this space and weight feature. My invention and discovery permits designing substantially to any desired bore and stroke relationship.

For one example, an engine may be designed having a small bore and an exceptionally long stroke within a very small space and likewise an engine of fairly large bore and very short stroke may be designed for the same small space. So much for the space feature, and now as to the weight feature: In the engine in common use and of conventional design having the rigid crank chain linkage, the stresses in power production are concentrated necessarily upon parts of relatively small area and consequently the said parts are necessarily of relatively heavy construction to absorb the stresses incident to high-speed reciprocation. By providing an engine of my discovery and invention involving the employment of liquid as the power transmitting means, the said stresses may be distributed over relatively large areas and therefore the parts may be made of much less weight and of much simpler and economical construction—particularly more compact.

Through the rigid mechanical linkage in the conventional internal combustion engine, the piston is compelled to apply its maximum pressure at the minimum leverage position of the crankshaft and can only apply a reduced pressure to the maximum leverage of the crankshaft when the piston is halfway down in its stroke. At this point of the stroke the pressure above the piston has been greatly reduced through expansion and loss of heat through cylinder walls. Thus, there results a great loss of power and efficiency. In the engine of my invention, the increased leverage of the power transmitting liquid type of engine over that of the conventional crank chain type is still further augmented by the provision of the abutment members of my invention.

Another important advantage of my invention made possible by the use of a liquid power transmitting means, operating in place of conventional rigid connecting rods, is that by immersing all the principal moving parts of the engine in a liquid, which serves both as a coolant and lubricant, the use of non-metallic parts is made feasible, if desired, to substitute them for metallic members. Many such materials are adaptable for usage under this submerged condition, particularly synthetic and plastic moldable materials. Hard phenolics and phenolics with fibrous inclusions are particularly adaptable, as well as organic materials, such as rubber, woods, and flexible synthetics. Phenolics with a cloth filler may be employed in my invention as they are capable of withstanding extreme bearing pressures with only water used as the lubricant.

Various liquids may be employed for the liquid operating as "connecting rods," or the power transmitting liquid means. The use of mercury, silicones, tetracresyl silicate (liquid heat), or other high temperature resistant liquids for a liquid piston, or for power transmitting means, are advantageous due to their high boiling points,

which permits in my engine, higher cylinder temperatures with a resulting higher fuel efficiency. In general, the engine of my invention is adaptable to use fuels other than liquid fuels, for example, powdered coal, producer gas such as that made from organic material, coal, straw, and waste wood products. Obviously, the device of my invention is adaptable to the use of fuels widely differing fundamentally in character.

My invention is particularly adaptable to providing an engine of much more efficient type to operate as, or to do the work of, the conventional diesel type engine.

Objections to diesel engines as heretofore commonly constructed are as follows:

Engines of the diesel type are inefficient because their power is applied through a mechanical linkage which operates angularly thereby forcing the piston's circumferential surface against the cylinder walls with great force resulting in inefficient sliding friction and great wear. Accordingly, the maximum power at the piston head is only partly available for producing net turning effort. As great pressures are thus constrained by the mechanical linkage and bearings, there is generated a considerable amount of frictional heat which escapes through the cooling system and is thus not available as useful power.

The conventional diesel engine mechanism is formed of parts of great complexity, which of necessity must be accurately machined and fitted. Particularly, accurate finishing is required of crankshafts, bearings and valving means.

The problem of lubricating the diesel engine, as now constructed, requires extensive special provisions. Lubrication requirements along with other limiting features, which characterize the diesel engine of today, renders it necessary to operate it at a maximum of about 200° F. for its coolant.

Throughout the history of diesel engines, engineers have striven to reduce the weight per horse power developed. The considerable weight and space required in relation to the net horse power produced is one reason why the potential field for utility of diesel engines has been restricted to services permitting such weight. In short, the excessive weight, space, and high manufacturing cost per horse power of the conventional diesel engine has definitely restricted its field of application.

The cost of construction of the diesel type of engine is relatively high. The employment of mechanical linkage rigidly limits the minimum size of the moving parts, the angularity of power application to crank leverage, cylinder bore and stroke, and the revolutions per minute. The diesel type of engine to be fully reversible requires additional complexity of mechanism.

A primary object of my invention is to provide a power developing or transmitting device operating on the diesel cycle which overcomes and solves the deficiencies above noted, and particularly to produce a mechanism characterized by the following features: Its increased efficiency; Its simplicity—being of a type by which its parts or for most part may be formed by die stamping; Employment of phenolic plates in place of metal; Welding assembly; Compactness; and Non-use of special lubricating oils; Operating at temperatures up to twice as high as presently employed; Greatly increased horse power per unit weight; and greatly increased effectiveness of the fuel consumed thereby permitting an increase of the available power.

A further advantage is that liquids are characterized by being substantially non-compressible yet highly mobile. As a power transmitting means such liquids do not require additional lubrication and may be subject directly to cooling action.

Features which characterize my invention are:

(1) Balanced volumetric relationship;

It is fundamentally important to locate the axis of rotation of the power transmitting liquid rotatable displacement member with respect to the partitioning means, such that the displacement member will displace equal volumes of the power transmitting liquid in each partitioned space or chamber, thereby insuring equal reciprocating piston-like bodies in the working chambers (i. e., the chamber corresponding to the cylinder in the conventional engine). Also, such balanced relationship provides equal working fluid (i. e., the force developing or expandible source of power) volumetric working spaces (corresponding to the compression spaces in the conventional internal combustion engine).

(2) Predetermined operative spaced relationship between the acting surface of the reciprocating body (liquid or interposing member piston or interposed buoyant leveling body) as respects the working fluid and the rotating displacement member.

A primary purpose of my invention is to employ the power transmitting liquid not only as a power transmitting liquid but also as a liquid sealing means to maintain a definite predetermined relationship between the top of the liquid column and the eccentric displacement member. This is important in order to have a definite fluid volume for the working chamber or cylinder. While on one hand it is important to have a definite fluid volume in the working cylinder at each stroke of the engine, it is also equally necessary to have the relationship of the top of the liquid column and the displacement member uniformly maintained. The power transmitting liquid, it will be understood, operates as a flexible linkage means in connecting the forces developed in the fluid chamber to the eccentrically mounted displacement member to rotate the shaft. Where the periodic force-developing fluid reacts directly again the surface of the piston-like column of liquid we have the simplest form of my invention as respects such elements.

In connection with the above are the means of maintaining the power transmitting liquid at a predetermined level by means of the use of a conventional surge chamber and an adjustable mechanical liquid displacing means operating upon the power transmitting liquid. This is one of the means for maintaining the uniform spaced relationship of the top of the liquid column and the displacement member. Any employment of a conventional sliding seal as a packing manifestly clearly involves wear and when it is remembered that the piston must reciprocate very rapidly, it is evident that very shortly there will develop such wear, as to permit leakage of air or fluid, particularly when there is a minus pressure on the underside of the piston. By providing a trapped interposed liquid seal such wear and leakage is prevented.

(3) "Cylindrical Ring" and sealing of power transmitting liquids in compartments;

To use a liquid as a power transmitting means, obviously, involves its confinement to definite channels to render available its incompressible characteristic. To the degree that the structure

of the engine permits leakage by so much is the efficiency of the engine lessened. Thus, the matter of proper sealing is fundamentally requisite in establishing and maintaining the "predetermined spaced relationship" set forth above.

5 A primary purpose of my invention is to provide sealing means so that pressures developed in a compartment are efficiently employed through shaft rotation. Accordingly, my invention and discovery involves various means of providing insured sealing of the power transmitting liquid, for example, (a) movable partitioning members including within their faces rockable surface contacting sealing elements; (b) annular idling member (herein referred to as "cylindrical ring") to alter relative pressure and velocity relationship, thereby achieving high sealing and low wearing factors; (c) means providing for augmenting and maintaining pressures upon the interlocked sealing element; (d) means providing for trapped interposed liquid sealing against fluid leakage which would destroy "predetermined spaced relationship" between the parts as set forth above; (e) means providing turbulence by establishing a counter flow of the liquid or interrupting the continuous flow, thus further reducing the efficiency of flow through a given orifice so that the leakage is further reduced; (f) means creating multiple orifices to further reduce the leakage in combination with inducing turbulence; and (g) means for minimizing the areas subject to being acted upon by unseating pressures acting upon partitioning members to disengage them from their sealing contact with the displacement member.

35 (4). Abutment;

The purpose of the abutment member of my invention is to selectively guide and direct the pressure developed in a compartment to that part 40 of the displacement member desired, that is, to that part of the displacement member whereby the maximum rotative effort may be obtained from the power transmitting liquid at its maximum pressure, and also for applying pressure 45 upon a selected portion of the circumference of the displacement member, that is, under a selected range of leverage of said displacement member. This provides also a new method of reciprocating power application to a rotating shaft by applying maximum pressures to maximum 50 rotating leverage differentiating thereby from the conventional crank chain rigid connection rod linkage which applies maximum pressures at minimum rotative leverage. It will be remembered that the rigid crank linkage applies 55 the maximum pressures very close to dead center. This abutment arrangement permits application of pressures to rotating effort at any desired degree between the maximum and the minimum 60 rotative leverage thereby being in direct contrast to the inflexible conventional "crank chain" linkage which operates in a sequence of rigid relationship.

(5) Cooling means;

65 The academic rule is that the hotter the cylinders are operated, the more efficient is the internal combustion engine. However, there are certain practical limits. The cylinder cannot be allowed to become too hot because then pre-ignition occurs in both diesel as well as in the Otto cycle.

One of the objects of my invention herein is to provide a means where the combustion can take place at a higher temperature than is now commonly employed. In accomplishing this, I

provide means for the removal of excessive heat accumulation by internal cooling, as distinguished from external cooling, as is conventionally employed. This is done through the medium of the power transmitting liquid.

(6) Efficient scavenging of gases or fluids to be exhausted;

One of the basic limitations of an expansible chamber engine is the providing for rapid scavenging of the fluids to be exhausted. A primary object of my invention and discovery is the overcoming of this limitation and providing for increased efficiency relating thereto.

(7) Flexible design dimensions permitting fitting and adapting to space requirements;

A feature characterizing my invention in using power transmitting liquid as a flexible connecting rod, is that it may have relatively great horse power in relatively small space as compared to conventional rigid connecting rod engines. This compactness is due to the engine of my invention providing for the use of a short liquid flexible member as a substitute for conventional rigid connecting rod and at the same time providing for avoiding the high side thrust, high wear and high friction which is inherent with the use of a short rigid connecting rod in the conventional engine. On the other hand, when the conventional engine employs a long rigid connecting rod to reduce said thrust, wear and friction, its resulting space requirements are greatly increased and thus results a large bulky engine of excessive weight. However, when desired, or conditions require, the engine of my invention provides for a long flexible liquid connecting member, as when the displacement member of the engine is submerged in water in a well or mine shaft and the working cylinders are placed above ground.

(8) Widely spaced working cylinders from rotatable displacement member;

(9) Economical construction and minimum machining;

A primary object of my invention is to provide an engine of economical construction by reason of the fact that it may be integrally formed of cast parts, which require a minimum of machining for precision fitting.

Other characterizing features are inherent in the various structures disclosed.

By "working cylinder" is meant herein the forms of means as follows: (a) Cylinder and liquid piston as illustrated in Fig. 1 and Fig. 2; (b) Cylinder with piston member (1) interposed between the power transmitting liquid and the explosive fluid or (2) in case of pump device, interposed between the power transmitting liquid and the material, gaseous or liquid, being acted upon, as shown in Fig. 9.

The above mentioned general objects of my invention, together with others inherent in the same, are attained by the mechanism illustrated in the following drawings, the same being preferred exemplary forms of my invention:

Figure 1 is a cross sectional view of a preferred form of engine embodying my invention;

Fig. 16 is a view in longitudinal section illustrating valve operating means of the modified form shown in Fig. 12;

Only preferred forms of my invention are set forth. Of these the one disclosed in Fig. 12 and connected figures constitutes a particularly preferred form. It is to be remembered that any particular form or combination of forms of my invention may be employed to meet particular operating requirements.

The more simple of the preferred forms for a wide general use of my invention (Figs. 1 and 2) has housing 100, with driving shaft 101 preferably centrally located with respect to the housing 100 and partitioning means 104 and 105 to provide balanced operation. On shaft 101 is fixedly and eccentrically mounted a rotatable displacement member 102 of cylindrical form. Upon displacement member 102 is freely mounted a ring member 103 of cylindrical form which in operation rotates with slippage with respect to displacement member 102 in order to provide a rate of sealing surface rotation less than that of the displacement member 102, thereby minimizing wear of contacting surfaces. Reciprocal sliding partitioning members 104 (upper) and 105 (lower) are preferably located in the vertical plane through the axis of the shaft 101 or axis of rotation, each bearing upon ring member 103 through rockable upper and lower sealing mem-

bers 106 and 107 respectively. Upper and lower guide blocks 108 and 109 respectively mount in recesses 110 and 111 the sliding partitioning members 104 and 105. Rockable sealing members 112 may be mounted in upper guide 108 to bear upon upper partitioning member 104 and rockable sealing member 113 may be carried by partitioning member 104 to bear against the sides of recess 110. Lower guide block 109 may have rockable sealing members 114 bearing against lower partitioning member 105. Said member 105 may also have rockable sealing members 115 mounted therein to bear against the walls of recess 111. Recess 110 has opening 116 which is connected by tube 117 to opening 118 in recess 111.

Guide block 108 has arm 119. Guide block 109 has arm 120. Arms 119 and 120 serve as partial partitions. They also serve as pivotal bearings for movable abutments 121 and 122 respectively and cause leading end portions 125 and 126 thereof to bear upon ring 103 to form a liquid tight seal therewith. The following end portions 127 and 128 of abutments 121 and 122 respectively are provided with valve seats 129 and 130, which seat upon valve seats 131 and 132 carried respectively on guide blocks 108 and 109, forming chambers 133 and 134. Openings 135 and 136 in said chambers 133 and 134 respectively are connected by tube 137.

The housing 100 with its end walls 138 and 139 form a liquid confining chamber composed of two compartments 140 and 141, preferably equal, which are provided with liquid 142. This liquid is reciprocated and caused to function piston-like and also as a power transmitting means, thus taking the place of conventional rigid connecting rods. The housing 100 has extensions 143 and 144 forming fluid expansion chambers 145 and 146. Air inlet tubes 147 and 148 located respectively in chambers 145 and 146, connect with air supply tubes 149 and 150 respectively and these tubes connect with air supply tube 151 which is connected to a conventional air compressing mechanism 152. Air inlet tubes 147 and 148 have conventional streamlined poppet valve members 153 and 154 respectively. Valve members 153 and 154 have springs 155 and 156 respectively and are operated by push bars 157 and 158. Chambers 145 and 146 communicate with exhaust outlets 159 and 160 respectively through conventional poppet valves 161 and 162, operated by push bar 157, respectively as respects chamber 145 and valves 163 and 164, operated by push bar 158, as respects chamber 146. Each of these valves has springs 165 of identical construction. Push bars 157 and 158 are operated by rocker arms 166 and 167 respectively which arms in turn are operated by push rods 168 and 169. These push rods 168 and 169 are operated by cams 170 and 171 mounted on shaft 101.

Conventional fuel injectors 172 and 173 are inserted in chambers 145 and 146 respectively and are supplied with fuel by conventional fuel pumps which are not shown. Fly-wheel 174 is mounted on shaft 101. Partitioning members 104 and 105 are forced by liquid 142 under pressure to bear tightly against ring 103 to seal off the liquid in one compartment from that in the other. Recess 111 communicates with compartments 140 and 141 by means of check valves 175 and 176 respectively which are adapted to supply liquid under pressure from the liquid in that compartment 140 or 141 whichever is under the highest pressure. Liquid level regulator 177, operatively disposed in

housing extension 178, regulates the liquid level in expansion chambers 145 and 146.

In Fig. 2 packings 183 and 184 are mounted in end members 138 and 139, about shaft 101 to prevent leakage of liquid 142 from housing 100. Displacement member 102 and ring member 103 are in close sealing contact with end walls 138 and 139. Flywheel 174 is shown mounted on shaft 101.

10 The mode of operation of said engine of my invention is as follows:

The stage of operation illustrated in Figure 1 is that combustion and expansion has taken place in chamber 145, valve 153 has opened and is admitting scavenging air from air compressor 152. Thus, exhaust gases are being forced past exhaust valves 161 and 162 into exhaust outlet 159. The expansion in chamber 145 has placed liquid 142 in compartment 140 under pressure and thereby forced eccentrically mounted displacement member 102 to rotate to position shown. This actuating of member 102 has displaced liquid 142 in compartment 141 forcing it to rise in chamber 146 thereby compressing the fluid therein and raising its temperature to the ignition point of the fuel. The fuel at that point is injected into chamber 146 through fuel injector 173. It will be understood that just prior to the raising of the liquid 142 in chamber 146, air intake valve 154 has been closed by valve spring 156. Likewise exhaust valves 163 and 164 have been closed by associated springs 165.

Upon ignition and expansion taking place against liquid 142 in compartment 141, the liquid 35 is placed under pressure. This liquid 142 under pressure is directed against rotatable displacement member 102 at its point of greatest leverage by abutment 121 which causes the displacement member 102 to rotate and turn driving shaft 101.

40 As expansion forces cause displacement member 102 (note position of its *x* and *y* axis) to turn and move displacingly into compartment 140, see Fig. 3, orbit 182 is shown at dotted line, the liquid in chamber 146 drops to the level at which the liquid is illustrated in chamber 145 due to the liquid occupying the space vacated by the eccentric portion of the displacement member 102. Thus a complete cycle of the engine operating as a two-cycle engine has been set forth and it is apparent that the operation of the parts in compartments 140 and 141 are the same at successive or alternate stages.

60 By having tube 117 connecting recesses 110 and 111 is provided hydraulic means for sealingly 55 pressing partition members 104 and 105 with equal pressures against ring 103—providing a positive mechanical sealing contact. The rockable members 106 and 107 are adapted to conform to the curved surface of ring 103 at all positions of its rotation. The rockable sealing members 112 and 114 together with rockable sealing members 113 and 115 also insure effective sealing. Manifestly, as one partition member is moved displacing into its recess, the reciprocal 65 liquid is forced through tube 117 to the opposite partition member to maintain it in positive sealing relation. Additional booster pressure is applied to this reciprocal liquid through check valves 175 and 176 from that particular compartment 140 or 141 having the greatest pressure. To minimize localized friction wear due to high velocity and high pressures on small area, ring 103 having a wide bearing area on displacement member 102 and a slower rotational rubbing 70 speed is interposed between the high velocity

speed of the displacement member 102 and the localized pressure area of the rockable member mounted within the end portion of the sliding partitioning members 104 and 105.

The said relatively slower speed or rotation of the ring member 103 has also the important beneficial function of producing turbulence in the liquid and establishing additional restrictive orifices as respects the end walls 138 and 139 and rotative members (ring 103 and displacement member 102) in assisting efficient sealing relation between the compartments 140 and 141. The power transmitting liquid 142 tends to escape from the compartment under pressure to the other compartment having less pressure through the orifice-like opening represented by the necessary running clearance between the end walls 138 and 139 on the one hand and the rotating displacement member 102 with its ring 103. By providing difference of rotational speeds for the idly mounted ring 103 and the displacement member 102, my invention creates a turbulent condition in the liquid thereby utilizing the liquid itself to resist passing through the clearance orifice and thereby assists effective sealing between compartments as respects the end portions of the displacement member. In addition, the ring 103 in conjunction with displacement member 102 creates a plurality of restrictive orifices across the line of liquid leakage so that opposition to leakage is greatly augmented. The restrictive orifice areas are established in the following order: First, the liquid must pass from the compartment under pressure between the ring 103 and the end wall affected; second, between the end of the displacement member 102 and the end wall; and third, between the ring 103 and the end wall affected to reach the compartment having lesser pressure.

Let it be particularly noted that by providing the rockable sealing members 106 and 107 extending substantially fully across and only across the full face of the end portions of partitioning members 104 and 105, it is manifest that a novel effective sealed partitioning is provided. By having the rockable sealing members 106 and 107 so extending fully across and only across the face of the end portions, prevents substantially any surfaces being exposed to high pressures periodically developed in compartment 140 and 141 from acting against such end portions to unseat them, that is, to operate to such extent to nullify the sealing. The efficiency of the machine depends in large measure upon preventing leakage of the power transmitting liquid from one compartment to the other.

The functioning of the abutments 121 and 122 is as follows:

The resilient means 123 caused the leading edge of abutment 121 to extend into the path of rotation of displacement member 102 and as member 102 continued its rotation abutment 121 pivoted on arm 119, thereby causing the valve seat 129 on the following edge to become unseated as respects its seat 131. Thus, trapped power transmitting liquid 142 between ring 103 and abutment 121 is permitted to escape into chamber 133 and thence through opening 135 into the tube 137. This liquid under pressure then enters chamber 134 through opening 136 which forces abutment 122 against resilient means 124 into unseated position as respects seats 130 and 132, thus permitting the liquid under pressure in tube 117 to escape into compartment 140 which at this stage is an area of lesser pressure as it is

not under expansion or compression pressure. When the trapped liquid ceases flowing from chamber 133, resilient means 124 forces abutment 122 to rotate, thereby bringing valve seats 130 and 132 into closed position (see Fig. 3) which, acting as a check valve, prevents escape of liquid 142 from compartment 140 to 141. In this wise, opposing pressure to the rotation of the displacement member 102 is removed by its transfer to the area of lesser pressure, namely, to compartment 140. Thus the function of the abutment 121 is manifest as a means of protecting or holding off the expansion pressure of liquid 142 in compartment 141 as respects the upper circumferential portion of the displacement member 102 and allows the expansion pressure of liquid 142 in compartment 141 to act directly only upon the lower portion of the displacement member 102, i. e., at its greatest leverage. As displacement member 102 continues to rotate, resilient means 123 and the liquid under compression (as distinguished from expansion) pressure causes the leading edge of abutment 121 to bear tightly and liquid sealingly against ring 103.

This situation is diagrammatically represented in Fig. 4 which further illustrates how the expansion force is applied to the longest lever arm (that part of the axis X between the center of driving shaft 191 and the periphery of displacement member 102). The long axis of the eccentric displacement member 102 is identified herein as "X," while the short axis at right angles to X, as "Y." In the drawing, Fig. 4, the net driving force on the longest lever arm is represented by the large arrows 179. The pressure forces on this longest lever arm necessary to balance or offset the forces resisting turning effort are shown by small arrows 180—the resisting forces being identified by small arrows 181. Thus, the great power advantage gained through the providing of abutments 121 and 122 is apparent—it being understood that abutment 122 operates in a manner paralleling that of abutment 121. But the abutments 121 and 122 function to hold off the counter rotation forces and direct the application of maximum expansion forces against the greatest available leverage of the displacement member 102 and thereby provides a pronounced mechanical efficiency.

Figure 1a represents a modified form of my invention where a plurality of cylindrical rings are employed. On shaft 195 is fixedly mounted a displacement member 191 and on this displacement member are idly and floatingly mounted cylindrical ring members 188, 189, and 190. The cylindrical ring 188 contacts the partitioning member 192 through rotatable block member 194—the partitioning member 192 is slidably mounted in guides 193.

The mode of operation of this plurality of cylindrical members 188, 189, and 190 is: Each multiplies the action of the single cylindrical ring hereinabove set forth and has the added action of providing for inducing liquid turbulence in sealing.

In Fig. 4a, sealing rings 290 and 291 respectively extend into recesses 292 and 293 in rotatable displacement member 294 and ring member 295 of cylindrical form. Passageways 296 and 297 permit liquid pressure to engage and press outwardly sealing rings 290 and 291. This construction reduces leakage. In Fig. 4b a liquid sealing ring 298 in a displacement member 299 is pressed outwardly by resilient means 300 which might be of rubber. Be it noted that in both

the forms shown in Fig. 4a and Fig. 4b resilient means are provided for urging outwardly the sealing rings 290 and 291, and 298 respectively—in Fig. 4a liquid alternately under pressure and in Fig. 4b a resilient means in the form of a spring 300. In 4c, the modified form of partitioning member 303 is provided with recesses 304 positioned across the direction of leakage flow as an impediment and to create a turbulent liquid condition for reducing to a minimum the leakage flow.

In the modified form of my invention illustrated in Figs. 5, 6, 7 and 8, a two-working cylinder engine of my invention operating two cycle is shown having valve ports in the side or end members of the housing and arcuately movable abutment members described as follows: This form of my invention has housing 320 and end or side walls 342 and 343 with driving shaft 321 preferably centrally located with respect to the housing 320. On shaft 321 is fixedly and eccentrically mounted a rotatable displacement member 322 of cylindrical form. Upon displacement member 322 is freely mounted a ring member 323 of cylindrical form which in operation rotates with slippage with respect to displacement member 322. Reciprocal sliding partitioning members 324 and 325 are preferably located in the vertical plane through the axis of the shaft 321 or axis of rotation, each held in sealing relation with the ring member 323 by resilient members 326 and 327 respectively. Upper and lower guide blocks 328 and 329 respectively mount in recesses 330 and 331 the sliding partitioning members 324 and 325, said recesses having openings 332 and 333 connected by tube 334. Likewise said guide blocks 328 and 329 pivotally mount abutments 335 and 336 in bearings 337 and 338. Said abutments have rockable sealing members 339 and 340 and preferably end sealing members of the character shown in Fig. 4a or 4b. Partitioning members 324 and 325 and ring 323 divide the chamber formed by the housing 320 into two compartments 347 and 348. Abutment 335 has valve operating extension 341.

This modified form of my invention is characterized by having valving means in the form of a disk 344 with air inlet ports 345 and exhaust ports 346 in compartment 347, while the disk 344 also has air inlet ports 349 and exhaust ports 350 in compartment 348. This disk 344 may be oscillatingly mounted on shaft 321 and against end wall 343. In the end or side wall 343 are corresponding and registering ports as follows: In compartment 347 are air intake ports 351 and exhaust ports 352 and likewise in compartment 348 are air intake ports 353 and exhaust ports 354. Be it noted that the exhaust valving means may be in the end wall opposite to that in which the air intake ports are located if uniflow scavenging is desired. Disk 344 has valve disk extensions 356 and 357 serving as mountings for springs 358 and 359. Housing 320 has shelf extensions 360 and 361 which also serve as mountings for said springs 358 and 359. Disk 344 has slots 362 and 363 in which stop pins 364 and 365 extend, said pins being fixedly mounted in end wall 343. End wall 343 also has rocker pin 366 extending through disk slot 367, which pin 366 mounts rocker arm 368. End wall 343 has ports 369 and 370 connected by tube 371. In disk 344 are slots 372 and 373 registering with ports 369 and 370. Air intake manifold 374 communicates with air intake ports 351 and 353 in the end wall 343. Exhaust manifolds 375 and 376 connect

with exhaust ports 352 and 354 in end wall 343. Fuel injectors 377 and 378 are located respectively in the upper part of compartments 347 and 348.

The general mode of operation of this modified form of my invention is similar to that set forth for the form shown in Figure 1 except as to the valving means which operates as follows: As shown in Fig. 5 the air in compartment 348 is being compressed by the liquid 379 being displaced by the rotating of the displacement member 322. By such rotation, the abutment 335 has been caused to move arcuately thereby causing valve operating extension 341 to move upwardly and engage extension 357 which rotates valve disk 344 to bring into open port registration, air inlet ports 345 and exhaust port 346 in the disk 344 by causing them to register with air inlet port 351 and exhaust ports 352 respectively in end wall 343. Thus fresh air enters compartment 347 and exhaust scavenging takes place. At the same time, in compartment 348 valve ports are continued in closed or non-registering position.

Upon displacement member 322 continuing to rotate, spring 359 and pressure of liquid moves abutments 335 downward whereupon spring 359 rotates clockwise disk 344 until pin 365 through opening 381 in extension 357 engages the spring 359 whereupon rotation ceases, leaving all valve disk ports closed in both compartments. Be it noted that the space between the ports in each compartment and in end wall 343 is double the width of a port opening so that the valve disk 344 may angularly oscillate to move through three positions, one for open registration and two positions for closed to alternately open and close ports to scavenge the cylinder of exhaust gases. Thus all ports are closed when firing and compressing the charge.

Upon continued rotation of displacement member 322 abutment 335 moves outwardly and engages rocker arm 368 which causes valve disk 344 to rotate clockwise to open ports in compartment 348, spring 358 returns disk 344 to closed port condition as rotation of displacement member 322 continues. Extension 364 has opening 380 to pass pin 364 precisely as described above for spring 357. Thus a cycle of operation of the valve means has been set forth.

In the above both inlet and exhaust ports are located in a disk at one end of the housing. Obviously, to provide unidirectional scavenging, the inlet port could be in a disk at one end and the exhaust port in a disk at the other end of the liquid chamber—each disk being of identical construction shown and described above except each disk would have only one type of port.

The modified form shown in Figs. 9, 10 and 11 of the device embodying my invention is characterized by having a fixed form of abutment, and having moving pistons in the working cylinders which are actuated by the liquid member functioning as a flexible power transmitting means in lieu of the conventional mechanical rigid or rod linkage, i. e., "crank chain linkage."

A housing 390 with end walls 391 and 392 has a driving shaft 393 rotatably mounted therein. A rotatable displacement member 394 may be key mounted on said shaft 393. A ring member 395 of cylindrical form is idly mounted upon said displacement member 394 as hereinabove explained. Sliding partitioning sealing members 396 and 397 are disposed in a plane through the center of said shaft 393, or axis of rotation.

These sealing members may be provided with rockable sealing members 398 and 399 respectively bearing upon ring 395. Said sliding partitioning sealing members 396 and 397 may be also provided with laterally rockable sealing members 400 and 401 respectively, bearing on guide blocks 402 and 403 formed integrally with the housing 390. Said guide blocks also may be provided with rockable members 404 and 405. Sliding partitioning sealing members 396 and 397 are mounted in recesses 406 and 407 respectively in guide blocks 402 and 403, and said recesses also have openings 408 and 409 respectively. A tube 410 connects opening 408 with liquid control box 411 having upper and lower chambers 412 and 413 separated by a partition 414 having valves 415 and 416. Lower chamber 413 has partition 417 dividing lower chamber 413 into compartments 418 and 419. Tube 420 connects liquid control box 411 with opening 409.

Displacement member 394 with partitioning members 396 and 397 divide the liquid confining chamber in housing 390 into compartments 421 and 422 to confine liquid 423. Tube 424 connects compartment 422 to compartment 418 of control box 411. Tube 425 connects compartment 421 with compartment 419 of liquid control box 411.

Fixedly mounted abutment 426 mounted on guide block 402 and housing 390 is operatively disposed with respect to the rotatable displacement member 394 having a concave face 427 lying adjacent the outer orbit of the displacement member 394 and its ring 395. Abutment member 426 is hollow to provide trapped liquid receiving chamber 428. In face 427 is spring operated valve means 429.

Diametrically opposite to fixed abutment member 426 is fixed abutment 430 mounted on housing 390 and guide block 403 similar in construction and operation to member 426. That is, it has concave face 431 and trapped liquid chamber 432, face 431 having spring operated valve means 433. Valve means 429 and 433 are positively operated by cam 434 through push rods 435 and 436 connected to rocker arms 437 and 438 which respectively engage valve means 429 and 433.

Compartment 421 has working fin radiating cylinder 439, i. e., explosion or expansion chamber with a piston 440 characterized by novel features of my invention as follows: The underside of said piston is formed with a depending wall 441 which maintains close floating contact with liquid 423 as it provides a buoyant chamber 442 between wall 441 and the piston head 443 which has the deflecting body 444 adapted to deflect scavenging air to the upper portion of the cylinder 439 to effect uniform scavenging of exhaust gases. Piston 440 is also characterized by having a continuous dependent skirt 466. This piston 440 has guide rod 445 slidably mounted in bracket 446 carried by housing 390 in order to prevent rotation of piston 440 to maintain deflecting body 444 in registering relationship with air intake ports 447 and exhaust ports 448. Cylinder 439 has a fuel injector 449 which is supplied by conventional fuel pump not shown.

Compartment 422 has air compressing cylinder 450 with floating air compressing sealing ring 70 carrying piston 451. Cylinder head 452 has conventional spring operated valve means 453 and 454. Valve means 453 admits air from intake pipe 455 and valve means 454 admits air to air storage chamber 456 formed between wall 457 and

housing 390. Air storage chamber 456 communicates with working cylinder 439 through air intake port 447. Exhaust port 448 in cylinder 439 opens into exhaust pipe 458.

The mode of operation of said form of my invention is as follows: Piston 440, Fig. 9, is shown at bottom of its stroke with scavenging taking place. Its power stroke has rotated the displacement member 394 to its minimum displacement position with respect to compartment 423 and to its maximum displacement position in compartment 422, and which has caused liquid 423 in compartment 422 to force piston 451 to its upper limit of travel. This in turn has compressed the air in cylinder 450 and caused said air to open and flow through valve 454 into storage chamber 456 during the period of the rise of piston 451, so that it becomes available to flow under pressure through port 447 after the latter is opened by being uncovered by the descent of piston 440 in cylinder 439. As fly-wheel 459 revolves it maintains continued rotation of displacement member 394, thereby forcibly expelling liquid trapped in chamber 460 formed between concave face 427, ring 395, and partitioning member 396, through valve 429 which has been opened by cam 434 and associated linkage. Thus, the liquid 423 passes into chamber 428, compressing the air contained therein. This compressed air at a later stage expels the liquid 423 from said chamber 428 when displacement member 394 and its associated ring 395 has rotated to a position which allows valve 429 to open by said air pressure. The same operation takes place as respects chamber 421 and its associated chamber 461 formed at a later stage between displacement member 394, concave face 431, and partitioning member 397, when displacement member 394 rotates to a position indicated by dotted line 462.

In the event that there is leakage of liquid 423 past rockable sealing members 402, 403, 404 and 405, liquid 423 is initially supplied to housing 390 and control box 411 and the latter's associated tubes. When compartment 421 is under maximum pressure then this pressure forces liquid 423 through tube 425 into liquid control box 411; thence past valve 415 into chamber 412 thus placing liquid in tubes 410 and 420 and recesses 406 and 407 under augmented pressure which in turn forces partitioning members 396 and 397 into tightly sealing relation with respect to ring 395. Likewise when the liquid 423 in compartment 422 is at maximum pressure, the same action as just described takes place for compartment 421. In this case, the pressure is communicated through tube 424 to liquid control box 411, thence through valve 416 into chamber 412. Thus, a cycle of operation is completed.

In Fig. 11 the application of potential or available power is diagrammatically illustrated with respect to the angular position of the displacement member 394 at 0°, 45°, 90°, 135°, and 180° when abutment means are provided in conjunction with the use of liquid functioning as a flexible power transmitting means between the working cylinder and the driving shaft. 0° position is that position of the piston at its maximum upward travel due to the maximum displacement position of the rotatable displacement member. The other positions follow in order as rotation of the displacement member progresses. At all positions, the available power is represented by small arrows 463 and the amount of transmitted power is shown by long arrows 464. It will be noted in positions 0°, 45° and 90° that the amount of trans-

mitted power is equal to the amount of available power. It will be understood that the available power decreases and has the progressively reduced number of small arrows shown above the piston as the piston descends due to expansion and loss of heat. At said positions of 0°, 45° and 90° the abutment is operative in directing the application of the transmitted force to the displacement member 394. In positions 135° and 180°, the abutments are not operative and the transmitted power is lessened with respect to the available power. The dotted line 465 indicates that no power is being transmitted.

Figs. 12, 8, 12a, 13, 14, 15 and 16 show a further modified form of an engine embodying my invention showing movable abutment members and arcuately moving partitioning members coactingly connected with resilient means together with other improved valving features.

In housing 540, a driving shaft 541, preferably centrally located with respect to the housing 540, has eccentrically mounted a rotatable displacement member 542, on which is idly mounted a ring member 543 of cylindrical form, which in operation rotates with slippage with respect to displacement member 542. Arcuately movable partitioning members 544 and 545 are pivotally mounted on shafts 546 and 547 respectively and sealingly bear on housing 540. Said shafts extend through end wall 548 with bearing mountings as respects one end thereof, while the other end has a closed end bearing in wall 549 (see Fig. 13). Said partitioning members 544 and 545 have rockable sealing members 550 and 551 which sealingly bear upon ring 543. On shafts 546 and 547 are mounted lever arms 552 and 553, respectively, the outer ends of which are operatively connected to a joining rod 554. On this rod 554 is mounted on one end portion a resilient member 555 which bears against the outer end portion of lever arm 552, through which said rod slidably passes in hole 556.

Partitioning members 544 and 545 together with displacement member 542 with its ring 543 divide the chamber formed by housing 540 into two compartments 557 and 558.

Arcuately moving abutments 559 and 560, having rockable sealing members 561 and 562 respectively, are mounted on shafts 563 and 564 respectively. Said shafts extend through end wall 548 with bearing mountings as respects one end thereof, while the other end has a closed end bearing in wall 549. On shafts 563 and 564 are mounted lever arms 565 and 566 respectively, the outer ends of which are operatively connected to a joining rod 567, Fig. 13. On this rod 567 is mounted resilient member 568 which bears against the outer end portion of lever arm 565, through which said rod slidably passes in hole 569. This construction corresponds to interconnecting means for partitioning members 544 and 545. On shaft 541 is preferably mounted flywheel 570.

Trapped liquid chambers 571 and 572 are formed between abutment members 559 and 560, partitioning members 544 and 545 and ring 543. Openings 573 and 574 in chambers 571 and 572 respectively are joined by tube 575 for establishing hydraulic interconnecting means as previously described for other forms of my invention.

Compartments 557 and 558 are provided respectively with working or expansion cylinders 576 and 577, having fuel injectors 578 and 579. In cylinders 576 and 577 are exhaust valve seats 580 and 581 and modified sleeve valves 582 and

583, in the upper end of which are exhaust ports 584 and 585 respectively with seats 586 and 587 at the top. At the bottom, said sleeve valves have inwardly projecting rings 588 and 589 (as shown 5 threadedly mounted to permit assembly). Beneath said rings are flexible annular sealing members 590 and 591. Stops 592 and 593 are mounted on the housing 540 to provide a lower limit of travel for the sleeve valves 582 and 583.

10 In sleeve valves 582 and 583 are pistons 594 and 595 which have tubular piston rods 596 and 597 extending downwardly through compartments 557 and 558 into double acting air compressing cylinders 598 and 599 respectively through packing 600 and 601. In pistons 594 and 595 are poppet valves 602 and 603 respectively which are seatingly mounted in tubes 596 and 597. Poppet valve 603 with stem 604 is slidably guided in a spider 605. Spring 606 is mounted on said stem 604. Poppet valve 602 is identically mounted in tube 596 but is not shown in the interest of brevity.

On the lower end of tubes 596 and 597, Fig. 12, are mounted air compressing pistons 607 and 608. In upper part of cylinders 598 and 599 are recessed air by-pass ports 609 and 610 respectively. Upper parts of cylinders 598 and 599 communicate with chambers 611 and 612 respectively having conventional spring loaded air intake valves 613 and 614 with seats 615 and 616 in wall 617 of air intake chamber 618. The bottom part of cylinders 598 and 599 communicates with air chambers 619 and 620 respectively, having conventional spring loaded air intake valves 621 and 622 with seats 623 and 624 respectively in wall 625 of air intake chamber 618.

On piston rod tubes 596 and 597, Fig. 12, are collars 626, 627, 628, and 629 respectively engageable with slidable members 630 and 631 having ports 632 and 633 registerable with ports 634 and 635 in pressure relief and liquid make-up boxes 636 and 637. Since these boxes are of identical construction only box 637 will be described in detail. Port 635 opens into chamber 638 communicating with chamber 639 in which is spring loaded relief valve 640. Chamber 639 communicates through opening 641 with reservoir 642. Chamber 638 has spring loaded suction valve 643 through which liquid is drawn from reservoir 642.

50 The mode of operation of the modified form of my invention set forth above is as follows:

The general mode of operation of this form of my invention so far as the fundamentals are concerned is the same in general as that set forth herein for the other forms. Partition members 544 and 545 arcuately mounted are held in sealing tight engagement with ring 543 as follows: As said ring 543 follows the eccentric orbit of displacement member 542 there is directly imparted a primary reciprocal motion to partitioning members 544 and 545 and this in turn is imparted to lever arms 552 and 553 and simultaneously also a secondary motion is imparted to said partitioning members and arms due to change in their spaced relationship induced by the eccentric character of displacement member 542. That is, said partitioning members 544 and 545 may move in opposite directions and their lever arms 552 and 553 move in the same direction during different phases of the rotative cycle but always they are maintained in close sealing contact with respect to ring 543 due to the action of resilient means 555 on joining rod 554. Tube 575 provides 60 and 70 for relieving the pressures in whichever chamber 75

571 or 572 the liquid may be trapped by transferring the trapped liquid to that chamber having the lesser pressure. The above construction makes possible in a practical way the arcuate movement of partitioning members 544 and 545 to effectively sealingly bear upon rotating displacement member 542 through ring 543.

Arcuately mounted abutment members 559 and 560 have identical mounting construction tying them in cooperative action and mode of operation as said partitioning members 544 and 545, so that their mode of operation will not be repeated in the interest of brevity.

As shown in Fig. 12, cylinder 576 has fired and piston 594 is at the bottom of its stroke whereby it has contacted and moved sleeve valve 582 downward opening the exhaust port 584 in the top from its seat 580 to allow exhaust gases under pressure due to expansion to escape through exhaust pipes 644 (cylinder 577 has exhaust pipe 645). After said first expulsion of exhaust gases and resulting drop in pressure within the expansion chamber of sleeve valve 582, valve 602 is opened by the air pressure within tubular piston rod 596. Thereupon there occurs inflow scavenging of the exhaust gases leaving undiluted air in said expansion chamber, which is now available for compression and the injection of fuel at the next explosion phase of the cycle.

Valve 602 will be forcibly closed due to its inertia and its spring, when piston 594 is forced upwardly by the liquid in compartment 557, when said liquid is displaced in compartment 557 by the rotation of displacement member 542. This liquid displacement forces flexible sealing ring 590 into sealing contact with ring 588 carried by sleeve valve 582, and moves said sleeve valve 582 with said flexible ring 590 and piston 594 upwardly until seat 586 of sleeve valve 582 seats against exhaust valve seat 580. Piston 594 then continues to move upwardly with intake valve 602 in tightly closed position and compression of the air in said sleeve valve 582 is compressed for the next cycle of fuel injection. The scavenging air under pressure in tubular piston rod 596, which, as stated above, opened valve 602, was supplied as follows: As piston 607 descended, air previously drawn in through valve 621 and which was augmented in volume by the previous upward air compression stroke which by-passed the piston from its upper side to its underside through bypass ports 609 when the piston uncovered its lower portion. During its continued downward stroke valve 613 opens by atmospheric pressure and air is admitted to chamber 611 from air intake 618. When piston 607 reaches the bottom of its stroke, valve 613 is closed by its spring. When piston 607 started downwardly valve 621 was closed by its spring.

Piston 595 and its associated parts operates in opposite phase in the same manner as said piston 594 and hence its operation will not be further described.

Pressure relief and make-up box function as follows: Port 633 in slidable member 631 is in open register with port 635, being so positioned by the previous downward stroke of tubular piston rod 597 and its collar 628. When the liquid in compartment 558 came under pressure due to the rotation of displacement member 542, said pressure was transmitted through ports 633 and 635 to liquid in chamber 638. When this pressure exceeds the set pressure of the spring loaded relief valve 640, the valve opens and the pressure is relieved by liquid passing into chamber 639, 70

thence through opening 641 into reservoir 642. As tubular piston rod 597 nears its upper limit of travel, collar 629 engages slidable member 631 and moves port 633 upwardly and out of registry with port 635. Thus, sealing off any further escape of liquid into reservoir 642 while the next expansion stroke takes place. As piston 595 nears the bottom of its stroke, collar 628 engages slidable member 631 forcing it downward until port 633 is again in registry with port 635. If at this time there is any deficiency of liquid in compartment 558 due to any leakage from said compartment 558, liquid from reservoir 642 is forced under atmospheric pressure through valve 643 into chamber 638, thence through ports 635 and 633 and into compartment 558. Valve 643 is then closed by its spring and the liquid in said compartment 558 is then ready for the next displacement by the rotation of displacement member 542.

In Fig. 15, a modified form of the tubular piston rod and scavenging air admission means of Fig. 12 is shown suitable for aspiration for Otto cycle operation or by timed fuel injection means, i. e., in this form there is not a fuel injector means at the top of the expansion cylinder corresponding to injection means 578 in Fig. 12, but there is substituted a conventional fuel ignition means, such as spark plug 655. Air intake valve 650, corresponding to air intake valve 602 in Fig. 12, is floatingly guided by spider bracket 651 mounted within tubular piston rod 652 which has mounted on its upper end portion piston 653 which in turn reciprocates within sleeve valve 654, which in turn reciprocates in cylinder 660. Tubular fuel conveying and air intake valve positive opening means 656 is fixedly mounted in an air compression cylinder head 657 and is connected to fuel supply line 658. Tube 656 is closed at its upper end which functions to open valve 650 as shown. Also at its upper end are laterally disposed jet holes 659 to permit fuel to enter scavenging air stream from air compressing cylinder 666 by suction induced by the flow of the scavenging air past the jet holes 659 after valve 650 has been opened and the first rush of undiluted air has started scavenging the exhaust gases. The first portion of undiluted scavenging air is followed by the air fuel mixture which rises in cylinder 660.

When the scavenging air has scavenged the exhaust gases, then the sleeve valve 654 is pushed upwardly by the power transmitting liquid member 661 so that valve seat 662 in sleeve valve 654 is sealingly engaged with registering seat 663. Thus, the scavenging is accomplished with undiluted or pure air so that the fuel air mixture next following is conserved exclusively for combustion instead of being partly used for scavenging as in the conventional two-cycle engine. As said liquid 661 moves the sleeve valve 654 upwardly, piston 653 is likewise moved upwardly by the liquid 661 operating through opening 664 so as to bear against the underside portion of piston 653 which in its upward travel closes valve 650 floatingly mounted thereon.

Fuel mixture is admitted to fuel tube 658 and to its extension 656 by suction created by the rapid passage of scavenging air past ports 659 as above set forth from a carburization or a fuel atomizing mechanism 665 of standard common practice carburetor design.

Fig. 16 illustrates a second modified form of the mechanism illustrated in Fig. 12 as respects valving of the working cylinder which does not employ the sleeve type valve as in Figs. 12 and 15—poppet type exhaust valves 675 being sub-

stituted therefor. In poppet type exhaust valves 675, the valve stems 676 are floatingly mounted in piston 677 which carries valve stem cylinders 678 in sealed relation against the power transmitting liquid member 679. Piston 677 is slidingly mounted in working cylinder 680 having a water cooling jacket 681. Stems 676 are provided with resilient means 682 which act to close valves 675 when not being held open by the downward travel of piston 677.

Intake valve 683 is floatingly mounted within piston tubular member 684 which in turn has mounted therein a valve opening rod 685 which is fixedly secured to lower cylinder head 686. Fuel is admitted through fuel injector nozzle 687.

Expansion of gases in cylinder 680 forces piston 677 downward, thereby opening poppet valves 675 by engaging collars 688 mounted on valve stems 676 at the lower portion of travel of the piston 677. The downward travel of piston 677 also causes engagement of stem 683a of valve 683 mounted thereon with rod 685, thereby opening same and admitting scavenging air from tubular member 684. This scavenging air supply is similarly provided for as in Fig. 12 by pistons 607 and 608.

As the scavenging of the cylinder 680 is completed, the piston 677 is moved upwardly by liquid member 679 and in so doing poppet valves 675 are closed by resilient means 682 against exhaust valve seats 689. Intake air valve 683 is closed by its inertia as piston 677 moves upwardly against it. Valve stem cylinders 678 obviously function as valve stem 676 receiving means.

The mode of operation of the inventions herein described has been set forth in conjunction with the structural descriptions in order to render the same more clear and readily understood.

I claim:

1. A device of the character described comprising a housing forming a liquid chamber; a shaft extending through said liquid chamber; a working cylinder connected to said liquid chamber; a periodically occurring force-developing fluid in said working chamber; power transmitting liquid forming a reciprocating liquid piston-like body in said working chamber; an eccentrically mounted rotatable displacement member mounted on said shaft whereby said power transmitting liquid may be reciprocated; movable partitioning members located above and below said displacement member, each of which members contact said displacement member, each of which members contacts said displacement member in substantially a vertical plane through said shaft, thereby, in conjunction with said displacement member, dividing said liquid chamber into a plurality of compartments; and two abutment members arcuately movably mounted in said compartments, one having one end pivotally mounted in the upper wall of said liquid compartment and the other member having one end pivotally mounted in the lower wall of said compartment, the other end of said members contacting said displacement member in a plane extending substantially horizontally through said shaft whereby the pressure of said power transmitting liquid is applied to a selected segment of said displacement member as respects each compartment, that is, when the leverage arm of said displacement member is greatest in that compartment.

2. In a device of the character described, a housing forming a liquid chamber; a shaft extending through said liquid chamber; a working cylinder connected to said liquid chamber; power

transmitting liquid forming a liquid piston-like body in said working cylinder; a periodically occurring force-developing fluid in said working cylinder; an eccentrically mounted rotatable displacement member mounted on said shaft whereby said power transmitting liquid may be reciprocated; a piston mounted in said working chamber having a poppet valve; an air compression means; and a tubular piston means connecting said piston and said air compression means, said tubular piston extending through said power transmitting liquid whereby compressed air periodically passed through said tubular piston scavenges spent gases in said working cylinder and cools said power transmitting liquid.

3. A device of the character described comprising a housing forming a liquid chamber; a shaft extending through said liquid chamber; a working cylinder connected to said liquid chamber; power transmitting liquid forming a reciprocating liquid piston-like body in said working chamber; an eccentrically mounted rotatable displacement member mounted on said shaft whereby said power transmitting liquid may be reciprocated; movable partitioning members mounted on said housing of said liquid chamber on opposite sides of said displacement member, each partitioning member contacting said displacement member on opposite sides thereof substantially in a plane through the axis of said shaft, thereby, in conjunction with said displacement member, dividing said liquid chamber into a plurality of compartments, and a movable abutment member disposed in each of said compartments resiliently held against said displacement member as to one end portion in contacting said displacement member in a plane extending substantially through said shaft and forming one side of said compartment otherwise bounded by said partition member and said displacement member, from which compartment a pressure developed in said power transmitting liquid is substantially excluded whereby the pressure of said power transmitting liquid is applied to a selected segment of said displacement member as respects each compartment, that is, when the leverage arm of said displacement member is greatest in that compartment.

4. A device of the character described comprising a housing forming a liquid chamber; a power transmitting liquid in said chamber; an eccentrically mounted rotatable displacement member mounted on said shaft whereby said power transmitting liquid may be reciprocated; movable partitioning means mounted on said housing of said liquid chamber on opposite sides of said displacement member, each partitioning member contacting said displacement member on opposite sides thereof substantially in a plane through the axis of said shaft thereby, in conjunction with said displacement member, dividing said liquid chamber into a plurality of compartments; an abutment member disposed in each of said compartments extending as a yielding wall between the housing and the displacement member limiting and directing the periodically developed pressure of said power transmitting liquid in each compartment substantially to predetermined segments of said displacement member whereby the pressure is applied to the displacement member during the period when said displacement member presents its greatest leverage arm in that compartment; a changeable volume trapped liquid chamber bounded by said displacement member, abutment member and partitioning member in

each compartment; and a conduit interconnecting said trapped chambers whereby the pressure developed in one trapped chamber may be released in the other.

5. A device of the character described comprising a housing forming a liquid chamber; a power transmitting liquid in said chamber; an eccentrically mounted rotatable displacement member mounted on said shaft whereby said power transmitting liquid may be reciprocated; a movable partitioning means mounted on said housing of said liquid chamber and extending to said displacement member thereby dividing said chamber into a plurality of substantially equal compartments; an abutment means disposed in each of said compartments extending as a yielding wall between the housing and the displacement member limiting and directing the periodically developed pressure of said power transmitting liquid in each compartment substantially to predetermined segments of said displacement member, whereby the pressure is applied to the displacement member during the period when it presents its greatest leverage arm in that compartment; and rockable concave faced blocks sealingly and surface-bearingly contacting the displacement member, said blocks being carried by said partitioning and abutment members.

6. A device of the character described comprising, a housing forming a liquid chamber; a shaft extending through said liquid chamber; a working cylinder connected to said liquid chamber; power transmitting liquid in said chamber forming a reciprocating liquid body in said working cylinder; an eccentrically mounted rotatable displacement member mounted on said shaft whereby said power transmitting liquid may be reciprocated; a movable partitioning member mounted on said housing of said liquid chamber, thereby, in conjunction with said displacement member, dividing said chamber into a plurality of compartments; and an abutment member disposed in each of said compartments extending as a yielding wall between the housing and the displacement member limiting and directing the periodically developed pressure of said power transmitting liquid in each compartment substantially to predetermined segments of said displacement member whereby the pressure of said liquid is applied to the displacement member during the period when it presents its greatest leverage arm in that compartment.

7. In a device of the character described comprising, a housing forming a liquid chamber; a shaft extending through said liquid chamber; a working cylinder connected to said liquid chamber; power transmitting liquid forming a reciprocating liquid body in said chamber; an eccentrically mounted rotatable displacement member mounted on said shaft whereby said power transmitting liquid may be reciprocated; movable partitioning members mounted on said housing of said liquid chamber on opposite sides of said displacement member, each partitioning member contacting said displacement member on opposite sides thereof substantially in a plane through the axis of said shaft and, in conjunction with said displacement member, dividing said liquid chamber into a plurality of compartments; and an abutment member in each compartment movably mounted on said housing of said liquid chamber located on opposite sides of said displacement member and contacting said displacement member on opposite sides substantially in a plane through the axis of said shaft, which plane is

normal to said first-mentioned plane whereby the pressure of said power transmitting liquid is periodically applied to a selected segment of said displacement member as the same is presented in each compartment in employing the greatest leverage of said displacement member.

8. In a device of the character described, a housing forming a liquid chamber; a shaft extending through said liquid chamber; a working cylinder connected to said liquid chamber; a power transmitting liquid in said chamber forming a reciprocating liquid body in said working cylinder; an eccentrically mounted rotatable displacement member mounted on said shaft whereby said power transmitting liquid may be reciprocated; a partitioning member mounted on the housing as to one end portion thereof and extending to and contacting said displacement member in dividing said liquid chamber into a plurality of compartments; and an abutment member disposed in each of said compartments having one end portion thereof in contacting relation with the displacement member at a point substantially midway between said partitioning members, said abutment member limiting and directing the periodically developed pressure of said power transmitting liquid in each compartment substantially to predetermined segments of said displacement member whereby the pressure of said liquid is applied to the displacement member during the period when it presents its greatest leverage arm in that compartment.

9. In a device of the character described, a housing forming a liquid chamber; a shaft extending through said liquid chamber; a working cylinder connected to said liquid chamber; a valve seat mounted in said working cylinder; a power transmitting liquid in said liquid chamber forming a reciprocating liquid body in said working cylinder; a slidable sleeve valve having an exhaust port valve seat in the top thereof registerable with said seat first-named, in each of said working cylinders, and a piston with a poppet valve reciprocally disposed within said sleeve valve, said sleeve valve being hydraulically lifted into closed position with respect to its exhaust port valve seat by said power transmitting liquid; a tubular piston rod connected to said piston in said working chamber and communicatively connected to said compressed air developing means, said tubular piston rod extending through said power transmitting liquid and functioning as a heat transfer means in cooling said power transmitting liquid; an eccentrically mounted rotatable displacement member mounted on said shaft whereby said power transmitting liquid may be reciprocated; a movable partitioning member mounted on said housing of said liquid chamber on opposite sides of said displacement member, each partitioning member contacting said displacement member on opposite sides thereof substantially in a plane through the axis of said shaft, thereby, in conjunction with said displacement member, dividing said liquid chamber into a plurality of compartments; and an abutment member movably mounted on said housing of said liquid chamber on opposite sides of said displacement member and contacting said displacement member on opposite sides substantially midway between the partitioning contacts with the displacement member whereby force is periodically applied to a selected segment of said displacement member in each compartment in employing its greatest leverage.

10. A device of the character described, com-

prising a housing forming a liquid chamber; a shaft extending through said liquid chamber; a working cylinder connected to said liquid chamber; power transmitting liquid forming a reciprocating body in said working cylinder; an eccentrically mounted rotatable member mounted on said shaft whereby said power transmitting liquid may be reciprocated; a movable partitioning member mounted on said housing of said liquid chamber on opposite sides of said displacement member, each partitioning member contacting said displacement member on opposite sides thereof substantially in a plane through the axis of said shaft; thereby, in conjunction with said displacement member, dividing said liquid chamber into a plurality of compartments; an abutment member disposed in each of said compartments, having one end portion thereof in contacting relation with the displacement member at a point substantially midway between said partitioning members, said abutment member limiting and directing the periodically developed pressure of said power transmitting liquid in each compartment substantially to predetermined segments of said displacement member, whereby the pressure of said liquid is applied to the displacement member during the period when it presents its greatest leverage arm in that compartment; and a resilient mechanically interconnecting means joining said abutment members whereby displacement of one abutment member by said displacement

member actuates the other into sealing position and whereby compensation is provided for the differences in movement of said abutment members.

HAL DE WAIDE.
